CLAIM

The ornamental design for an end protector for cylindrical articles, as shown and described.

DESCRIPTION

FIG. 1 is a top perspective view of an end protector device for cylindrical articles showing my new design;

FIG. 2 is a side view thereof;

FIG. 3 is a bottom view thereof;

FIG. 4 is a top view thereof, fully folded in a position for use;

FIG. 5 is a side view of FIG. 4, all sides being identical;

FIG. 6 is a top perspective view thereof, partially folded with the cylindrical article, one end protector and pallet shown in broken lines for illustrative purposes only.

*Fig. 1.**Fig. 2.**Fig. 3.*

*Fig. 4.**FIG. 5*

FIG. 6
